(57) **CLAIM**

I claim the ornamental design for a switcher, as shown and described.

DESCRIPTION

FIG. 1 is a bottom front perspective view of a switcher of the present invention;

FIG. 2 is a top front perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a cross-sectional view taken along the line 9-9 in FIG. 3 with the internal parts being omitted thereof.

The broken lines in the drawings represent portions of the switcher that form no part of the claimed design.

1 Claim, 9 Drawing Sheets
